UNITED STATES PATENT OFFICE

HARRISON L. STALEY, OF MARTINSVILLE, INDIANA

BOILER TUBE CLEANER

Application filed March 21, 1928. Serial No. 263,286.

My invention relates particularly to rotary tube cleaners operated at high speed for removing the scale from boiler tubes of small diameter.

5 The nature of this service entails great strain on the cleaner and it is the object of my invention to provide an improved type that will stand the shocks and strains incident to this severe duty and at the same time increase the cutting speed of the cleaner.

10 My aim has been especially directed, 1, to improve the strength and durability of such cleaners by novel arrangement of parts, 2, to provide facilities for sustaining the centrifugal pressure on the cutting member against the scale, and 3, to provide a cleaner with parts so arranged and secured together that any portion of it may be easily removed and replaced when found necessary.

15 20 With these and other desirable objects in view, attention is directed to the accompanying drawings in which Figure 1 is a side elevation of the assembled head in closed position; Figure 2 a front view of the cleaner; Figure 3 a sectional view on line A—A in Figure 1 with sliding frames expanded; Figure 4 is a perspective view of the body; Figure 5 is a perspective view of the sliding frame and Figure 6 a perspective view of a 25 link.

30 In the drawings the numeral 2 designates the body of the cleaner which is provided with front and rear heads 3, 4 preferably circular in shape, connected by two oppositely disposed longitudinal bars 5, said heads being slotted both transversely and longitudinally, the merging into and equal in width to the space between the bars 5 making in fact one extending slot in the body in which 35 a pair of outwardly sliding frames 6 carrying rotatable toothed cutters are movably mounted. The longitudinal slots in the front head member are further connected by a transverse slot 7 across the face thereof to afford facilities for housing the links 8 which

provide means for limiting the outward movement of the frames 6. The body is further provided with a centrally located hub 9 preferably threaded internally for attaching thereto the driving mechanism.

40 Centrally located on the web or tie bar 10 is a fixed stud 11 which projects forwardly of the body to engage slots 23 of the links 8. I find it necessary because of the very great vibration to which the cleaner is subjected, 45 to reinforce or brace the free end of the stud by providing on the body two forwardly extending ears 12 on each side of the forward transverse slot 7 and parallel to said stud with holes therein in alignment with hole in 50 the stud for receiving the cotter 13. In actual operation I have found that this cotter keeps the stud from working loose from vibration or jar.

55 The slideable frames 6 are preferably bifurcated, the arm members 14, 15 thereon having apertures for receiving cutter bolts or pins 16 on which are mounted rotatable toothed cutter wheels. It is desirable that these bolts be headed and carry conical shaped cutters 17 60 between the head and the link 8 thereon and cylindrical cutters 18 between the arm members and that the ends of the bolts be screw threaded to engage the threaded hole of the arm member 14.

65 To carry out one of the objects of my invention, the inward portions of the slideable frames are reduced in thickness longitudinally so that when mounted in the body they will have overlapping engagement. It will thus 70 be seen by this arrangement of parts that broad areas can be given the sliding surfaces of the frames in a body of small diameter. Since it is necessary that the frames have freedom of radial movement, the combined 75 thickness of the overlapping portion should be slightly less than the width of the engaging transverse slot. A head 20 on the frame extends forward of the tie bar 10 to prevent locking of the link 8 against said tie bar when 80 85 90 95

the cutter bolts are seated in the frames. In closed position the overlapping parts of the frames engage shoulders 19 and the head 20 engages the tie bar 10. I find it desirable to 5 reduce the width of the web 21 and to taper the edges thereof inwardly to prevent interference with cutters 18 when the frames are in closed position.

The outward movement of the frames 6 are 10 limited by links 8. These links are provided with overlapping ends of reduced thickness and hole 22 for receiving the cutter bolt 16 and a long slotted hole 23 to engage the stud 11. The diameter of the slot 23 should be 15 greater than the stud 11 so that any lateral movement of the links caused by vibration will be carried by the side walls of the transverse slot 7 instead of by the stud.

In assembling the cleaner, links 8 are 20 mounted on the stud 11 and the cotter 13 passed through the aligning holes. Frames 6 are then movably secured in the transverse slot of the body from each side thereof with the straight side of the frame members engaging the farther side of the said transverse slot as related to its direction of rotation. Cutters and links are then assembled on the bolts 16 in their respective relations and the bolts seated securely in the frames.

30 In this novel arrangement and relation of parts, I have discovered facilities whereby any part can be easily removed and replaced by a new part when necessary.

I have also discovered that in making the 35 slide frame bifurcated and in one piece and slidably mounting it in an extending slot in the body, strain on the cutter bolt and frame is removed and less breakages thereof occur.

I have further discovered that when a head 40 of this type strikes a projecting piece of scale, resistance to inward movement of the frame is offered by the friction produced by the arm members pressing against the sides of the extending transverse slot and that this frictional resistance to inward movement greatly increases the cutting speed and effectiveness of the cleaner.

I do not wish to confine myself to the exact 45 construction and arrangement of parts as herein described to attain these desirable results, since it is apparent that changes in details may be made without departing from the spirit and scope of my invention as defined in the appended claims.

55 I claim as new:

1. A tube cleaner comprising a body having a longitudinally extending transverse slot through the body thereof, a pair of overlapping frames slidably mounted in the 60 transverse slot and toothed cutters rotatably secured in said frames substantially as described.

2. In a tube cleaner, the combination of a body adapted to be rotated having a longitudinally extending transverse slot there-

through, a pair of overlapping slidable frames movably secured in the transverse slot, bolts secured to the frames, cutters mounted rotatably on said bolts, links connecting said bolts, to limit the outward movement of the slidable frames, said links being movably secured to a fixed stud. 70

3. In a tube cleaner, the combination of a rotary body having circular head members connected by two parallel bars, oppositely disposed longitudinal slots in the head members coinciding with the space between said bars, transverse slots through the head members connecting said longitudinal slots, a pair of outwardly sliding overlapping frames 80 engaging the transverse slot, bolts secured in the sliding frames and cutters mounted rotatably thereon.

4. A tube cleaner comprising a rotary body, a transverse slot through the body, a pair 85 of overlapping bifurcated frames carrying toothed cutters removably mounted in the transverse slot to slide outwardly, and means for limiting the outward movement of the frames thereof.

5. In a tube cleaner the combination of a body, a pair of outwardly sliding frames 90 removably mounted in the body said frames having front and rear arm members, bolts removably secured in the arm members, rotatable cutters mounted on the bolts, a fixed stud extending forwardly of the body, slotted links engaging both the bolts and said stud to limit the outward movement of the arms, substantially as described. 95

6. The combination of a body adapted to be rotated having front and rear head members connected by two longitudinally extending parallel bars, outwardly sliding frames, carrying bolts with rotatable cutters thereon 105 and movably secured between said bars, oppositely disposed longitudinal slots in the head members, a transverse slot across the face of the front head member connecting the longitudinal slots therein, a tie bar in the front head, a stud secured to the tie bar and extending forwardly in said transverse slot, slotted link members secured to the cutter bolts and engaging the fixed stud, forwardly projecting ears on the front head member, 110 and a pin to pass through the aligning holes in the fixed stud and projecting ears to secure the links in said transverse slot substantially as described. 115

7. A tube cleaner comprising a rotary body 120 having a longitudinally disposed transverse slot therethrough, a pair of frames carrying rotatable toothed cutters slidably mounted in said transverse slot and means for limiting the outward movement of the frames thereof, 125 said means consisting of a fixed stud secured to the body and slotted links engaging said stud and said slidable frames.

8. A tube cleaner comprising a rotary body, 130 slidable frames mounted in the body and ex-

tending inwardly beyond the axis of rotation of said body, rotatable cutters mounted in said frames and means for limiting the outward movement of said frames substantially as described.

9. A tube cleaner having a body adapted to be rotated having a longitudinally extending transverse slot through the body, overlapping frames having their overlapping portions reduced in thickness and slidably mounted in the transverse slot, rotatable toothed cutters mounted on the frames and means for limiting the outward movement of said frames.
